(57) **CLAIM**

The ornamental design for a smartphone case, as shown and described.

DESCRIPTION

FIG. 1 is a front isometric view of a smartphone case showing our new design;

FIG. 2 is a rear isometric view thereof;

FIG. 3 is a front view thereof;

FIG. 4 is a rear view thereof;

FIG. 5 is a left view thereof;

FIG. 6 is a right view thereof;

FIG. 7 is a top view thereof shown on an enlarged scale; and,

FIG. 8 is a bottom view thereof shown on an enlarged scale. The broken lines throughout the figures depict portions of the smartphone case that form no part of the claimed design.
